CLAIM

The ornamental design for a battery dust cover, as shown and described.

DESCRIPTION

FIG. 1 is a top perspective view of a battery dust cover according to an exemplary embodiment;

FIG. 2 is a first side elevation view thereof;

FIG. 3 is a second side elevation view thereof;

FIG. 4 is a first end elevation view thereof;

FIG. 5 is a second end elevation view thereof;

FIG. 6 is a top perspective view thereof on the top of a battery; and,

FIG. 7 is a side perspective view thereof on the bottom of a battery.

The broken lines shown in FIGS. 1–6 are for illustrative purposes only, and form no part of the claimed design.

The long dash-short dash lines shown in the Figures are for the purpose of illustrating the boundaries of the claimed design and form no part of the claimed design.

1 Claim, 5 Drawing Sheets
